DESIGN FOR A SHOE

James R. Brady, Highland, Ill., assignor to
Moulton-Bartley, Inc., St. Louis, Mo., a cor-
poration of Missouri

Application December 29, 1934, Serial No. 54,639

Term of patent 3½ years

To all whom it may concern:

Be it known that I, James R. Brady, a citizen of the United States, residing at Highland, Illinois, have invented a new, original, and ornamental Design for Shoes, of which the following is a specification, reference being had to the accompanying drawing, forming part thereof.

Figure 1 is a top view of the shoe.

Figure 2 is a side view of the shoe.

Figure 3 is a detail longitudinal vertical section through the shoe toe and is on a larger scale than Figures 1 and 2.

The novel design is characterized by parallel wavy upstanding cord-like ridges extending across a wide expanse of plain surface of the same color and accentuated by stitches, adjacent ridges being separated by wider bands of smooth surface.

I claim:

The ornamental design for a shoe substantially as shown and described.

JAMES R. BRADY.
